APPARATUS FOR FORMING SHOES OF THE
PREWELTED TYPE

Harvey A. Scholz, Milwaukee, Wis.

Application August 31, 1935, Serial No. 38,721

5 Claims. (Cl. 12—12)

This invention appertains to the manufacture of shoes, and more particularly to a novel apparatus for forming shoes of the pre-welted type.

5. Pre-welted shoes are generally thought of as being inexpensive shoes. However, considerable time and effort is expended in the making of these shoes, and usually a number of different operations and machines are employed to pull 10 the upper over the combined insole and middle sole, to properly last the upper in place and to hold the upper while the outsole is being secured to the middle sole portion and to the welt.

In certain instances it has been proposed to 15 use an adhesive to hold the upper in place over the edge of the combined insole and middle sole; in other instances nails, wires, and clamps have been employed. All of these operations are slow, tedious, and expensive, and none (to my knowledge) properly shapes the upper to the last and to the combined insole and middle sole to form 20 a well-shaped shoe of good appearance.

It is, therefore, one of the primary objects of 25 my invention to provide a single machine for effectively drawing in the upper over the last and the combined insole and middle sole, and for shaping the upper thereto, and for firmly holding the upper and welt in proper position during the securing of the outsole in place, 30 whereby a well-formed pre-welted shoe can be quickly and economically made.

Another object of my invention is the provision of means for supporting the welt laterally of the last, when the upper has been shaped 35 and drawn into place, so that the outsole (as the same is brought into place) can be firmly united to the welt at all points as well as to the middle sole portion of the combined insole and middle sole.

40. Another prime object of my invention is to provide laterally movable drawing-in plates shaped to conform to the configuration of the shoe being made for effectively engaging all parts of the shoe between the upper and welt for bringing the upper and welt over the combined insole and middle sole nailed to the last, and for holding the upper in such position during the securing of the outsole to the shoe.

45. Another salient object of my invention is the provision of laterally movable side drawing-in plates shaped to conform to the sides of the shoe and laterally movable drawing-in toe and heel tuck plates shaped to conform to the shoe, 50 with means for detachably holding the plates in

position, whereby the same can be replaced when worn, or for different shaped shoes, etc.

A further object of my invention is the provision of novel and simple means for operating all of the drawing-in plates from a single operating member, whereby said member can be conveniently actuated from a foot treadle, so that the hands of the operator will be left free to manipulate the shoe, outsole, etc. 5

A further important object of my invention is 10 the provision of means for initially operating the toe and heel drawing-in plates slightly in advance of the side plates, so that the toe and heel parts of the upper will be partly drawn into position prior to the bringing in of the side por- 15 tions of the upper.

A further object of my invention is the provision of means for moving the toe plates toward one another as the said toe plates move in over the last, whereby the toe of the shoe 20 will be properly formed without danger of tearing or cracking the leather.

A further object of my invention is the provision of means for shifting the parts of the toe and heel plates toward and away from one 25 another, whereby the said parts can be adjusted to the width of the particular shoe being made.

A further object of my invention is the provision of means for mounting the side, toe, and 30 heel plates on slide members, whereby said side, toe, and heel plates can be initially adjusted on the slide plates to conform to the size of the shoe being manufactured.

A further object of my invention is the provision of means for rockably mounting the side 35 drawing-in plates on their slide plates, whereby said side plates will automatically conform to the shape of the insole, so that a well-formed shoe is insured without danger of injuring the 40 leather in any way.

A still further object of my invention is to provide an improved machine of the above character which will be durable and efficient in use, one that will be simple and easy to manufacture, and one which can be placed upon the market at a comparatively small cost. 45

With these and other objects in view, the invention consists in the novel construction, arrangement, and formation of parts, as will be 50 hereinafter more specifically described, claimed, and illustrated in the accompanying drawings, in which drawings:

Figure 1 is a front elevation of my improved machine.

Figure 2 is an enlarged, central vertical section through one unit of the machine, taken substantially on the line 2—2 of Figure 1, looking in the direction of the arrows.

5 Figure 3 is a top plan view of one unit of the improved machine, the drawing-in plates being shown in their open position, with the last and shoe removed.

10 Figure 4 is a horizontal section taken substantially on the line 4—4 of Figure 5, illustrating the novel means employed for actuating all of the drawing-in plates.

15 Figure 5 is a fragmentary side elevation of the improved machine with the last and upper shown in dotted lines.

20 Figure 6 is an enlarged, detail plan view showing the combined insole and middle sole nailed to the last, with the upper disposed on the last and prior to being drawn in over the last and combined insole and middle sole.

25 Figure 7 is an enlarged, fragmentary, transverse sectional view through the last, the upper and the combined insole and middle sole, with the side plates in position for drawing in the upper over the last and combined insole and middle sole, the section being taken through the last substantially on the line 7—7 of Figure 6.

30 Figure 8 is a view similar to Figure 7, with the upper drawn into its proper position, and the outsole cemented in place, the view being taken substantially on the line 8—8 of Figure 9, looking in the direction of the arrows.

35 Figure 9 is a view similar to Figure 3, showing the position of the plates after the upper has been brought into proper position over the last and the combined insole and middle sole.

40 Figure 10 is a central transverse section taken through one unit substantially on the line 10—10 of Figure 9.

45 Figure 11 is a transverse section through one unit of the machine, taken substantially on the line 11—11 of Figure 9 looking in the direction of the arrows.

50 Figure 12 is a similar section taken substantially on the line 12—12 of Figure 9, looking in the direction of the arrows.

55 Figure 13 is an enlarged, fragmentary, top plan view similar to Figure 6, showing the upper drawn into the proper position with the outsole secured thereto.

60 Referring to the drawings in detail, wherein similar reference characters designate corresponding parts throughout the several views, the letter M generally indicates my improved machine, and the same includes a supporting frame 15, which can be constructed in any desired manner without departing from my invention.

65 As shown, the frame includes corner standards 16, which can be constructed from angle iron. The lower ends of the standards 16 can be flared outwardly, as at 17, to provide an enlarged base. The upper ends of the legs or standards can be rigidly united by front and rear connecting bars 18 and by side connecting bars 19.

70 Similar bars 20 are utilized for connecting the legs of the standards together adjacent to their lower ends. Diagonal struts 21 can be employed for further bracing the frame. Rigidly secured to the front and rear top frame bars 18 are front and rear supporting straps 22 to which are connected the companion machine units 23 and 24.

75 These units 23 and 24 are formed identically in construction, except that one is employed for making a shoe for the right foot and the other

is used for making a shoe for the left foot. The construction of the machine is such that an operator can conveniently make a pair of shoes for the right and left feet substantially at the same time. In view of the similarity between the units, only one of the same will be described in detail.

80 Each of the units includes a pair of spaced, parallel, longitudinally extending side plates 25 and 26, which are connected adjacent to their opposite ends by front and rear, transversely extending cross plates 27 and 28. The side plates 25 and 26 and the front and rear supporting plates 27 and 28 can be connected together in any desired manner, such as by the use of screws 29, and these 15 four plates provide a rigid frame in which the shoe to be made is placed.

85 The front and rear cross plates 27 and 28 define guideways 30 for receiving the side slide plates 31 and 32, which are adapted to move 20 toward and away from the center of the frame. Secured to the upper surface of the plates 27 and 28 are pairs of spaced, longitudinally extending guide strips 33, which receive therebetween the front and rear slide plates 34 and 35, which also 25 are adapted to move toward and away from the center of the frame.

90 The top frame defined by the side plates 25 and 26 and the front and rear cross plates 27 and 28 are connected to the main or base frame 15 in 30 any desired manner, such as by the use of corner upright posts 35', which are rigidly connected to the supporting plates 22 carried by said base or main frame. As shown in Figures 11 and 12, the corner posts 35' are rigidly connected to the top 35 frame where the side and cross plates overlap.

95 The side slide plates 31 and 32 and the front and rear slide plates 34 and 35 carry the drawing-in plates or blades for the upper. The side drawing-in plates or blades, indicated by the reference character 36, are carried by the side slide plates 31 and 32 in a novel manner, which will now be described.

100 Mounted on the upper surface of the slide plates 31 and 32 by means of centrally disposed pivot bolts or pins 37 are the blade-carrying blocks 38. The inner edges of the blocks 38 are rabbeted to receive the drawing-in plates or blades 36, and said blades are detachably and rigidly secured to the blocks by means of suitable fastening elements, such as screws 39. By this arrangement, the side drawing-in plates and the blocks 38 are free to rock on their slide plates.

105 By referring to Figures 3 and 9, it can be seen that the side drawing-in plates extend from the heel seat of the shoe to the toe and have their inner edges sharpened and shaped to conform to the configuration of the shoe being made. Thus, the blades are curved to take care of the 110 arch of the shoe and the like.

115 Normally, the carrying blocks 38 for the drawing-in plates 36 are held in their proper balanced position by means of expansion coil springs 39, which are fitted within suitable 65 openings formed in the outer edges of the blocks and in openings formed in stop ribs 40 rigidly secured to the top surface of the slide plates 31 and 32.

120 It can be seen, however, that when the slide plates 31 and 32 are brought in toward one another and the drawing-in plates 36 for the upper engage the upper to draw the same in over the last and insole, the blades can rock, so that the blades can automatically conform themselves to 75

the configuration and the position of the shoe. The means for operating the slide plates will be later described.

The front sliding plate 34 detachably and adjustably carries a pair of heel blades or plates 41, which are utilized for drawing in the upper over the last and the rear part of the insole. Any preferred means can be employed for adjusting the heel blades or plates 41, so that the plates can be moved toward and away from one another and thereby permit the same to be adjusted to a particular shoe size.

In the present instance, the heel blades 41 have been shown to be provided with transversely extending slots 42, through which protrude bolts 43 carried by the slide plate. Winged or similar nuts 44 can be threaded on the bolts for holding the heel blades in proper position.

The rear slide plate 35 hingedly carries like companion toe blades 45 and 46. These blades 45 and 46, like the blades 41, have their inner faces sharpened and curved to conform to the particular style of shoe being made. Suitable pivot pins or bolts 47 rockably connect the toe blades 45 and 46 to the inner ends of forwardly extending double-ended levers 48 and 49. These levers are in turn rockably mounted intermediate their ends on the slide plate 35 by means of pivot pins or bolts 50. At this point, it will be noted that a cover plate 51 is provided for overlying the levers 48 and 49, and suitable spacing plates 52 are disposed between the slide plate and said cover plate.

The outer corners of the toe blades 45 and 46 have formed therein guide slots 53, which receive guide bolts 54 carried by the slide plate 35. By this arrangement so far, it can be seen that by adjusting the levers 48 and 49 the toe plates 45 and 46 can be adjusted laterally to conform to the size of the shoe being made.

To adjust the levers 48 and 49, the same can have pivotally connected to their outer ends, by means of threaded pins or the like 55, nuts 56. These nuts 56 receive the oppositely threaded terminals of a turnbuckle screw 57.

The means for moving all of the slide plates toward and away from one another will now be described. The operating means for the slide plates includes an operating ring or annular plate 60 located directly under the top frame. This ring is mounted for turning movement through a portion of the arc of a circle and can be supported by means of depending posts 61 rigidly carried by the top frame plates.

As illustrated, the lower ends of the depending supporting posts are reduced in diameter and extend through guide slots 62 formed in said ring. The lower ends of the reduced terminals of the depending posts 61 carry nuts or the like 63 for engaging the lower face of the ring 60, and obviously suitable wear washers can be interposed between the operating ring, the depending posts, and the securing nuts or screws 63.

One side of the ring is provided with an outwardly projecting operating arm 64, which is engaged by the upper end of a foot-operated lever 65. This foot-operated lever is rockably mounted intermediate its ends on a stationary pivot bolt or shaft 66.

By referring to Figure 1, it can be seen that the shaft 66 extends transversely across the main frame 15 for both of the units for the left and right shoes, and hence both of the foot levers for the units are supported by this same

shaft. The lower end of each foot lever is provided with a suitable foot treadle 67, and by depressing the treadle, the upper end of the lever will move forwardly and engage the operating arm 64 and thus bring about the rotation of the operating ring 60.

To hold the ring and to return the same to its normal position, a relatively heavy expansion coil spring 68 is provided. One end of the spring is anchored to the ring adjacent to the arm 64, and the other end of the spring is anchored to the main frame. In order to hold the foot treadle 67 in a depressed position and the ring in its turned position against the tension of the coil spring 68, a suitable releasable lock can be provided.

As illustrated in Figure 1, the main frame can be provided with a rack bar 69, a selected tooth of which can be engaged by an angle bar 70 rigidly connected with the lever 65 adjacent to its lower end. By shifting the lever 65 laterally with the foot, the angle bar 70 can be disengaged from the teeth of the rack bar.

As previously indicated, the ring 60 is employed for actuating all of the slide plates, and hence the side slide plates 31 and 32 carry depending operating pins 71 and 72 respectively. The front slide plate 34 carries a similar depending operating pin 73, and the rear slide plate 35 carries a similar depending operating pin 74. The pins 71 and 72 are received in arcuate slots 75 and 76 formed in the ring 60. The pins 73 and 74 are received in similar arcuate slots 77 and 78. Upon rotation of the ring 60, the pins 71, 73, 73, and 74 following the contour of their respective slots, will be drawn inwardly thus forcing the slide plates toward one another.

It is desirable that the toe and heel plates move a fractional part of their full movement prior to the operation of the side shoe plates, and consequently the slots 75 and 76 for the pins 71 and 72, can have their inner ends formed substantially straight, as at 79, so that no movement will be imparted to the pins 71 and 72 upon the first turning movement of the ring.

To bring about the effective use of my machine for making different sizes of shoes, I have provided means for initially positioning the slide plates. Obviously, by changing the position of the slide plates and their pins relative to one another, the desired sizes of shoes can be accommodated. Hence, I have provided means for adjusting the pins 71, 72, 73, and 74 on their respective slide plates. Each of the adjusting means is the same, and hence only one will be described in detail.

Each of the said pins has secured to its upper end a slide block 80. This slide block rotatably receives the inner end of adjusting shaft 81. Relative movement between the shafts 81 and the guide blocks 80 is prevented by means of collars 82 secured to the shafts engaging the opposite ends of the guide blocks. The shafts 81 are threaded, as at 83, for a portion of their lengths, and these threaded portions are received in feed nuts 84 rigidly carried by the slide plates. Handles 85 are rigidly connected to the shafts 81, so that the shafts can readily be threaded into and out of the nuts 84 for shifting the mentioned operating pins and their guide blocks 80.

I lay great stress on the novel arrangement of the toe plates 45 and 46, in that these plates are so arranged as to efficiently draw and tuck in the toe part of the upper over the last and insole without tearing or cracking the upper.

The initial movement of the blades 45 and 46 is straight in toward the toe of the shoe, and after these blades have traveled a certain distance with their slide plate 35, the same are rocked inwardly toward one another for bringing the sides of the toe over the last and the insole.

The means for bringing the toe plates inwardly toward one another consists of rollers 86 carried by the side slide plates 31 and 32. These rollers are disposed in the path of the outer forward corners of the toe plates 45 and 46. Thus, during the operation of the machine, when the toe plates 45 and 46 have been brought straight inwardly toward the toe, and the side slide plates 31 and 32 move toward one another, the rollers 86 will strike the outer forward corners of the toe plates and swing these plates on their pivot 47. Contractile coil springs 87 can be employed for normally holding the toe plates in their open position.

It may be desirable to adjust the position of the rollers 86 relative to the toe plates, and hence these rollers can be mounted on pins carried by brackets 89. These brackets 89 can be slidably mounted on the slide plates 31 and 32 and can be held in any adjusted position desired by means of set screws or the like 90 extending through slots formed in said brackets 89 and into the slide plates 31 and 32.

In use of my improved machine M, the combined insole and middle sole, indicated generally by the letter S, is nailed to the last L, and the upper U with the welt W sewed thereto is fitted on the last. As shown in Figures 6 and 7, the combined insole and middle sole S includes a middle sole portion 91, which can be formed from leather or composition and an insole portion 92. The insole portion 92 is preferably formed from cork and is of a lesser width and length than the middle sole portion 91, so that a flange or rabbet will be formed entirely around the combined insole and middle sole S. The last with the assembled parts, is placed within the opening in the top frame over the drawing-in plates, and, if preferred, a support can be provided for the last. This support may consist of an adjustable supporting pin 93 carried by a bracket plate 94 bolted or otherwise secured to the main frame.

As previously intimated, a pair of the shoes is made substantially at one time, and thus the parts of the shoe for the left foot are placed in one unit and the parts of the shoe for the right foot are placed in the other unit. The operator can now press down on the foot treadles, one at a time, and the various drawing-in plates will be moved toward the last and engage the shoe between the upper and the welt, effectively drawing in said upper over the last and the flange part of the soles S until the inner edge of the upper and its welt engages the marginal surface of the middle sole portions 92 of the soles. This is easily and simply accomplished due to the arrangement of the blades, and the shoe upper is quickly and properly brought in over the last and the sole.

When the uppers have been properly brought in and lasted, an outsole O is coated with a quick-drying cement, and the exposed face of the middle sole and the welt can be similarly coated, if preferred.

The outsole O is now placed on the exposed face of the middle sole portion 92 and the welt and is left to dry, while another outsole is taken

and coated and is placed on the shoe for the other foot. The drawing-in plates form an effective means for holding the upper in its proper brought-in position while the outsole is being secured in place, and the blades also form a rigid support for the welt, so that a good contact is insured between all parts of the welt and the outsole.

As soon as the shoes are dry, the foot treadles are released and the completed shoes are removed from the machine. The machine is now ready to receive another pair of shoes to be made.

From the foregoing description, it can be seen that I have provided an exceptionally simple and durable machine for bringing about the quick and efficient forming of pre-welted shoes, with a minimum amount of effort on the part of an operator.

Changes in details may be made without departing from the spirit or the scope of my invention, but what I claim as new is:

1. A machine for forming pre-welted shoes comprising side upper forming and drawing-in blades, means for initially adjusting the position of the blades relative to one another according to the width of a shoe being made, toe and heel blades movable toward and away from one another, means for initially adjusting the position of the toe and heel blades according to the length of a shoe being made, means for synchronously actuating all of said blades, said toe and heel blades including independent sections, and means for adjusting the position of the sections relative to one another to conform to the width of a shoe being made.

2. In a machine for forming a pre-welted shoe, a top frame, for receiving a last for supporting a prewelted upper and a combined insole and middle sole, a slide plate on said frame movable toward the last, a toe forming and drawing-in blade carried by the slide plate, said blade including a pair of independent sections having sharpened, arcuate inner corners, adjusting levers rockably mounted intermediate their ends on the slide plate, pivot pins operatively connecting the forward ends of the levers to the blade sections, and means for adjusting the outer ends of the levers.

3. In a machine for forming a pre-welted shoe, a top frame adapted to receive a last for a pre-welted upper and a combined insole and middle sole, a slide plate on said top frame, an upper toe forming and drawing-in blade on the slide plate, said blade including a pair of independent sections, each having a sharpened, arcuate inner corner, a pair of double-ended levers rockably mounted intermediate their ends on the slide plate, means pivotally connecting the blade sections to the inner ends of the levers intermediate the ends of said blade sections, manual means for synchronously adjusting the levers, said blade sections having guide slots therein adjacent to their outer corners, and guide pins carried by the slide plate received in said slots.

4. A machine for forming a pre-welted shoe comprising a top frame, side slide plates on the top frame, upper forming and drawing-in blades for the sides of the shoe carried by said slide plates, a slide plate on said frame disposed between the side slide plates, toe forming and drawing-in blade sections carried by the last mentioned slide plate, means for actuating all of the slide plates toward the center of the top frame, and rollers on the side slide plates.

disposed in the path of the toe blade sections for moving said sections toward one another after predetermined movement of all of the slide plates.

- 5 5. A machine for forming a pre-welted shoe comprising a top frame, side slide plates mounted on the top frame, end slide plates mounted on the top frame, upper forming and drawing-in blades carried by the slide plates, a rotatable 10 operating member having arcuate slots therein, depending operating pins carried by the slide

plates received in said slots, means for rotating the operating member through a portion of a revolution, and means for initially adjusting the position of the pins relative to their slide plates including a guide on each slide plate, a block 5 slidably mounted in each guide, means connecting the pins with the blocks, and hand feed screws rotatably connected to said blocks and adjustably carried by the top frame.

10

HARVEY A. SCHOLZ.
